(57) **CLAIM**

The ornamental design for a camera lens cover, as shown and described.

DESCRIPTION

FIG. 1 is an upper perspective view of a first embodiment of a camera lens cover of our new design;

FIG. 2 is a lower perspective view of thereof;

FIG. 3 is a front view thereof;

FIG. 4 is a rear view thereof;

FIG. 5 is a right view thereof;

FIG. 6 is a rear view thereof;

FIG. 7 is a top view thereof; and

FIG. 8 is a bottom view thereof

FIG. 9 is an upper perspective view of a second embodiment of a pair of camera lens covers of our new design in a stacked configuration;

FIG. 10 is a lower perspective view of thereof;

FIG. 11 is a front view thereof;

FIG. 12 is a rear view thereof;

FIG. 13 is a right view thereof;

FIG. 14 is a rear view thereof;

FIG. 15 is a top view thereof; and

FIG. 16 is a bottom view thereof.

FIG. 17 is an upper perspective view of a third embodiment of a camera lens cover of our new design;

FIG. 18 is a lower perspective view of thereof;

FIG. 19 is a front view thereof;

FIG. 20 is a rear view thereof;

FIG. 21 is a right view thereof;

FIG. 22 is a rear view thereof;

FIG. 23 is a top view thereof; and

FIG. 24 is a bottom view thereof.

FIG. 25 is an upper perspective view of a second embodiment of a pair of camera lens covers of our new design in a stacked configuration;

FIG. 26 is a lower perspective view of thereof;

FIG. 27 is a front view thereof;

FIG. 28 is a rear view thereof;

FIG. 29 is a right view thereof;

FIG. 30 is a rear view thereof;

FIG. 31 is a top view thereof; and

FIG. 32 is a bottom view thereof.
